Primary Examiner—A. Hugo Word*Assistant Examiner*—M. Brown[57] **CLAIM**

The ornamental design for a soil guard, as shown and described.

DESCRIPTION

FIG. 1 is a front elevational view of the soil guard showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an isometric view showing a use thereof.

The broken lines shown in FIGS. 1 and 7 are for illustrative purposes only and form no part of the claimed design.
